CLAIM

I claim the ornamental design for a hanging bathroom scale holder, as shown and described.

DESCRIPTION

FIG. 1 is a front elevation view of the hanging bathroom scale holder showing my new design.

FIG. 2 is a rear elevation view thereof.

FIG. 3 is a left side elevation view thereof.

FIG. 4 is a top plan view thereof.

FIG. 5 is a bottom plan view thereof; and,

FIG. 6 is a perspective view thereof.

1 Claim, 5 Drawing SheetsFIG. 1

FIG. 2

FIG. 3

FIG. 4

FIG. 5

FIG. 6
